UNITED STATES PATENT OFFICE

2,628,003

SEED PACKAGE AND SEED DISTRIBUTOR

Frederick R. Maurer, New Boston, Mich.

Application June 19, 1947, Serial No. 755,623

3 Claims. (Cl. 222—336)

1

The present invention relates to seed packages and distributors and specifically to hand carried and operated devices adapted to dispense one or two seeds at a time.

Among the objects of the invention is a package device in the structure of which is embodied distributor means adapted to be quickly rendered operative to distribute the seed contained in the package.

Another object is a combined package and distributor that is economical and inexpensive to make and fill and one that will not easily get out of order or adjustment.

Still other objects and advantages will be apparent to those skilled in the art upon reference to the following description and the accompanying drawings in which

Fig. 1 is a front elevation, partly in section, of a package and distributor made in accordance with the present invention.

Fig. 2 is a side elevation of the same.

Fig. 3 is a plan view of a suitable blank for making the outer cover.

Fig. 4 is an elevational view of the plunger.

Fig. 5 is also an elevation of the plunger but taken at right angles to the view of Fig. 4.

In the drawing there is shown in Fig. 3 a blank 10 of suitable sheet material such as heavy paper, cardboard, cellophane or the like, provided with three openings and having a reduced end 10A.

The openings 10B are shown circular for the reception of a dowel 11 while the opening 10C is shown slotted and somewhat smaller than openings 10B. However, the size and shape of opening 10C will be determined by the size and shape of the particular seed to be packaged and dispensed.

The blank 10 is preferably creased as indicated at 10D so that it may be wrapped around filler pieces or spacers 12 and 12A and suitably fixed thereto as by stapling, glueing or otherwise.

As indicated in Figs. 1 and 2, the blank 10 is wrapped around the two fillers with the reduced end 10A lying on the outside. This produces a flat package having a hopper shaped space 13 between, piece 12 being triangular and piece 12A being a narrow straight strip.

The dowel 11 is arranged in the openings 10B and is sufficiently long to extend at both ends. This member acts as a plunger or sliding element and is provided at one end with a notch 11A and near its other end with a spiral groove 11B arranged part way around the dowel and having at its lower end an inclined surface 11D. The dowel is also provided with an elongated notch

2

11C at an intermediate location. This notch 11C is adapted to cooperate with a suitable projection 12B on filler strip 12A to limit the movement of the dowel plunger and prevent its rotation.

5 The spiral groove 11B, when the device is assembled, is in a location such that it moves past the opening 10C, which in turn is located near the lower end of the hopper 13. Near the upper end of the hopper space 13 is a filling opening, 10 normally covered by a short tab 13A which may be sealed or otherwise maintained closed. The spiral form of the groove 11B provides means for conducting the seed from the hopper 13 to a position opposite opening 10C which is in one of the 15 side faces of the package.

After the package has been formed and provided with the seed filling, a rubber band 15 is passed around the package and dropped into the notch 11A in the dowel 11. In order to prevent 20 interference of the band with movement of the plunger, it is preferred to provide the blank with a notched tab 16.

When the blank 10 is folded around the filler pieces 12 and 12A, the extreme end 17 of the 25 reduced portion 10A will overlie the opening 10C and the tab 16 will be adjacent thereto.

Where the device is being used in its role as a package, the portion 17 prevents leakage of the contained seed. But, when it is desired to dispense the seed, the portion 17 is lifted or bent up to uncover the opening 10C. The operator then holds the package upright and moves the plunger 11 up against the tension of band 15 and allows it to return to its lower position.

30 In moving upwardly, the inclined lower surface 11D of the spiral groove acts as a cam or wedge and positively ejects those seeds lying on it. In this operation, a few seeds will fall into the groove 11B which has moved up beyond the opening 10C and when the plunger returns, one or two of the seed may fall out. And, 35 as the dowel reaches the bottom of its stroke, more seed will drop into the groove onto the surface 11D and be discharged on the upstroke.

40 As indicated above, the opening 10C and the size of groove 11B will be such as to suit the particular seed, and the amount of seed to be discharged per stroke of the plunger.

45 I claim:

50 1. A seed package consisting of container produced by wrapping an elongated blank of suitable material about a pair of relatively thin filler elements, one of which is triangular in shape and the other a narrow elongated rec-

55 tangle, whereby to produce a hopper shaped seed

space within said container, a dowel-like plunger extending through said container adjacent the rectangular filler, said plunger having a spiral groove therein adjacent the lower end of said hopper and extending partly around the said dowel having its upper end open to said hopper and having at its lower end an inclined face, said dowel having also an elongated notch adjacent the upper end of said hopper, a projection on said rectangular filler piece adapted to enter said notch and thereby determine the stroke of said plunger, a discharge opening adjacent the bottom of said hopper and opening to said groove approximately at the upper end of said inclined face when said dowel is at the end of its down stroke and a resilient band extending around said package and over the upper end of said dowel.

2. A combined packet and seed dispensing container consisting of a flattened packet adapted to contain a quantity of seed, a round plunger extending lengthwise through said container, said plunger of such diameter as to fit closely between the front and back walls of the packet and being provided near one end with a spiral groove opening at its upper end toward the seed body and at its lower end toward a side wall of the packet and capable of receiving a small num-

ber of the seed, means for limiting the stroke of said plunger and a discharge opening in a side face of said packet communicating with said groove.

5 3. A combined packet and seed dispensing container according to claim 2 in which are included means for determining the length of stroke of said plunger and resilient means normally retaining said plunger at that end of its stroke at which the groove communicates with the discharge opening.
